UNITED STATES PATENT OFFICE.

WILLIAM L. LOWREY, OF BOSTON, MASSACHUSETTS.

LIQUID FOR AND PROCESS OF GENERATING A COMPOUND VAPOR AS A MOTOR POWER.

SPECIFICATION forming part of Letters Patent No. 296,197, dated April 1, 1884.

Application filed November 12, 1883. (No specimens.)

To all whom it may concern:

Be it known that I, WILLIAM L. LOWREY, a citizen of the United States, residing at Boston, in the county of Suffolk and State of Massachusetts, have invented certain new and useful Improvements in Liquids for and Process of Generating a Compound Vapor as a Motor Power, of which the following is a specification.

10 The object of my invention is to gain power in engines, and to economize fuel. Any steam-engine having a boiler of ordinary construction with a surface-condenser can be used.

My invention consists, first, in mixing water 15 slightly alkaline, but not to exceed one (1) per cent., with alcohol, either absolute, methylic, the alcohol of commerce, or of any other kind or name, jointly or separately, their mixtures or compounds in the proportions 20 hereinafter mentioned; secondly, in introducing the compound liquid thus formed into boilers and vaporizing the same by heat; thirdly, in the compound vapor so generated; and, fourthly, in using said compound vapor as a 25 motor power. The proportions of the alcohols or their compounds and water depend on the size of the boilers and the degree of pressure required. In small boilers—viz., boilers used 30 in engines of from two (2) to twenty (20) horse- power—equal parts of the alcohols, or their compounds, and water may be used for ordinary working-pressure; but if a lighter pressure than the ordinary working-pressure of the boiler is desired, the proportions of the alcohols or their compounds may be varied—*i. e.*, 35 sixty (60) per cent. of water to forty (40) per cent. of the alcohols or their compounds, and so on, varying the proportions of the water and alcohols or their compounds, if a still 40 lighter pressure is desired, to ninety (90) per cent. of water and ten (10) per cent. of the alcohols or their compounds. A larger percentage of the alcohols, their mixtures or compounds than is herein mentioned may be used 45 under certain circumstances and conditions; but such use is dangerous and hazardous, and I have therefore limited the percentage to fifty (50) per cent. as the highest that should be used in any case.

50 In large boilers—*i. e.*, boilers in engines of

twenty (20) horse-power and upward—the proportions of the liquids for ordinary working-pressure are: alcohols or their compounds, forty (40) per cent.; water, sixty (60) per cent. These proportions, the same as in smaller boilers, 55 may be varied by reducing the percentage of the alcohols or their compounds and increasing the percentage of water, where lighter than ordinary working-pressure is necessary or desirable, until the desired pressure is obtained. 60 The proportions of the liquids, however, must not be changed to more than ninety-five (95) per cent. of water or less than five (5) per cent. of the alcohols or their compounds. In most cases, in large boilers, the liquid compound need not contain more than ten (10) to twenty (20) per cent. of the alcohols or their compounds.

By varying the proportions of the alcohols or their compounds and water, as above directed, the degree of pressure can be increased or diminished, as required. As the same pressure cannot always be maintained in boilers of the same size, owing to atmospheric and other conditions, different proportions of the liquids 75 may be found necessary in such boilers in order to obtain a given pressure. To increase the pressure, the proportions of the alcohols or their compounds must be increased, and to diminish the pressure the proportions of the 80 alcohols or their compounds must be diminished, the degree of heat remaining the same.

When heat is applied to a boiler filled with the above-described compound liquid, the alcohols or their compounds will first vaporize 85 at a comparatively low temperature and the vapor pass into the steam-chamber. When the temperature is raised to two hundred and twelve degrees, (212°), the steam generated from the water will combine and mingle with the 90 alcoholic vapor, forming a new compound vapor possessing the elasticity and expansion of the alcoholic vapor and the volume and tension of the steam, the elastic expansion of the alcoholic vapor being imparted to the steam, 95 and the volume and tension of the steam being communicated to the alcoholic vapor. By the union of these qualities of the respective vapors the new compound vapor will be found to be capable of producing with the same de- 100

gree of heat at least twice the pressure or expansive power of steam, and with one-half the degree of heat a pressure equal to, if not greater than, steam. This result is due to the fact that 5 the alcoholic vapors surrounded and permeated by the steam become thereby superheated, and thus acquire a volume and tension nearly, if not quite, equal to steam. The alcoholic vapors, though superheated by the steam, are protected thereby, so that they do not decompose, 10 but distill over into liquid unchanged.

The compound vapor formed as above described can be controlled and managed with equal facility and safety to steam. As the 15 compound vapor passes into the cylinder and becomes condensed, the latent heat of the steam is given off to the lower or alcoholic vapors, maintaining their elastic tension, and enabling them to expand and force the piston forward to its full stroke. The compound vapor 20 protects the interior of the boiler, pipes, and cylinders from corrosion, and, being to some degree a lubricant, assists in lubricating the cylinder while in use. After the vapor has 25 been used, it passes into the condenser, is reliquified, returned to the boiler, and again used as before, without perceptible diminution in quantity or quality. There is, therefore, no loss in the liquid, or at least so slight a loss 30 as to be inconsiderable.

No changes in the construction of boilers suitable for generating steam is necessary or desirable.

Having thus fully described my invention, 35 what I claim, and desire to secure by Letters Patent, is—

1. A compound liquid to be used in engine-boilers to generate a vapor for a motor power, consisting of alcohol, either absolute, methyl- 40 ic, the alcohol of commerce, or of any other kind or name, either jointly or separately, their mixtures or compounds, and water in the following proportions, viz: for small boilers—*i. e.*, boilers of from two (2) to twenty 45 (20) horse-power—equal parts of water and alcohol or alcohols, their mixtures or com-

pounds; and for large boilers—*i. e.*, boilers of twenty (20) horse-power and upward—six (6) parts water and four (4) parts alcohol or alcohols, their mixtures or compounds, and the 50 modifications and variations of said proportions, substantially as described.

2. The process of generating a compound vapor as a motor power, which consists in mixing absolute and methylic alcohols, their 55 compounds or mixtures, or either of said alcohols or their mixtures or compounds, jointly or separately, with water in equal proportions for small boilers, and for large boilers six (6) parts water to four (4) parts absolute or methylic alcohols, their mixtures or compounds, and modifications and variations of such proportions, and subjecting the same to heat in engine-boilers the same as water is heated to generate steam, substantially as described. 60

3. A compound vapor generated by heat in boilers from water and alcohol, either absolute, methylic, the alcohol of commerce, or of any other kind or name, either jointly or separately, their mixtures or compounds, mixed in 70 the following proportions: in small boilers—*i. e.*, boilers of from two (2) to twenty (20) horse-power—equal parts of water and alcohol or alcohols, their mixtures or compounds; in large boilers—*i. e.*, boilers of twenty (20) horse-power and upward—six (6) parts water and four (4) parts alcohol or alcohols, their mixtures or compounds, and the modifications and variations of said proportions, substantially as set forth and described. 75

4. The improved method or process of operating steam or vapor engines, which consists in applying thereto the compound vapor herein described and claimed, substantially as set forth.

In testimony whereof I affix my signature in presence of two witnesses.

WILLIAM L. LOWREY.
